UNITED STATES PATENT OFFICE.

SIDNEY A. KELLER, OF NEW YORK, N. Y.

DESIGN FOR A SHIELD.

SPECIFICATION forming part of Design No. 36,044, dated September 9, 1902.

Application filed August 12, 1902. Serial No. 119,460. Term of patent 7 years.

To all whom it may concern:

Be it known that I, SIDNEY A. KELLER, a citizen of the United States, and a resident of New York, borough of Manhattan, in the county of New York and State of New York, have invented and produced a certain new, original, and ornamental Design for Shields, of which the following is a specification.

In the accompanying drawing I have shown a face view of the shield designed for attachment to leather and ebony goods.

The characteristic features of my design are the outline of the shield, the head and neck of a female figure, and floral decoration consisting of flowers, buds, leaves, and stems, the ornamentation being in relief.

Referring to the drawing, A represents the head and neck of a female figure, B B flowers, C a bud, and D D leaves and stems, all in relief, the portion E being left plain. 20

What I claim is—

The ornamental design for a shield, substantially as herein shown and described.

Signed at New York, borough of Manhattan, in the county of New York and State of New 25 York, this 11th day of August, A. D. 1902.

SIDNEY A. KELLER.
